UNITED STATES PATENT OFFICE.

GEORGE W. ARNOLD, OF DENVER, COLORADO.

ORE-SEPARATOR.

1,397,480.

Specification of Letters Patent. Patented Nov. 15, 1921.

Application filed November 6, 1920. Serial No. 422,198.

To all whom it may concern:

Be it known that I, GEORGE W. ARNOLD, a citizen of the United States, residing at Denver, in the county of Denver and State 5 of Colorado, have invented new and useful Improvements in Ore-Separators, of which the following is a specification.

The present invention is directed to improvements in ore separators, and has for 10 its primary object to provide an apparatus of this character so constructed that the ore will be effectively separated by agitation.

A further object of the invention is to provide an apparatus of this nature so constructed and arranged as to subject the pulp 15 to agitation in such a manner as to assure practically maximum separation of the ore.

A still further object of the invention is to provide a separator of this character 20 which is extremely simple in construction, durable, efficient in operation, and one which can be manufactured at a very small cost.

With these and other objects in view, this 25 invention resides in the novel features of construction, formation, combination and arrangement of parts to be hereinafter more fully described, claimed and illustrated in the accompanying drawings, in which:—

Figure 1 is a perspective view of the de- 30 vice.

Fig. 2 is a fragmentary transverse sec- 35 tional view.

Fig. 3 is a side elevation, partly in section.

Fig. 4 is a sectional view on line 4—4 of 40 Fig. 3.

Fig. 5 is a detail view of the apron ad- 45 justment.

Fig. 6 is an enlarged detail sectional view 50 to more clearly illustrate the manner in which the deck and riffles are connected.

Referring to the drawings, 1 designates 55 the deck, preferably formed from sheet metal, said deck having formed adjacent its rear edge a longitudinal pocket 2, the pur- 60 pose of which will appear later. A sheet 3 of linoleum is placed upon the upper surface of the deck 1, and resting on the sheet are the horizontal webs of the angle iron riffles 4 and 5, the former being somewhat greater in 65 height than the latter.

Suitably secured to the ends of the deck, 70 and abutting the ends of the riffles 4 and 5, are end plates 6, and adjustably supported by said plates is an inclined apron 7, the 75 lower end of which terminates in a vertical depending flange 8, which is disposed be-

tween the riffles 4 and 5, as clearly shown in Fig. 2 of the drawings, the purpose of which will later appear.

Associated with the front and rear edges 80 of the deck 1 are tailings and concentrates of the deck 1 are tailings and concentrates conducting aprons 9 and 10, respectively.

A pair of channel beams 11 are employed, and have their bases resting on any suitable support. Having their lower ends fixed 85 to the beams are resilient arms 12, four of which are preferably employed, said arms having their upper ends terminating in horizontal heads 13.

It will be observed that the clamping bolts 90 14 not only serve to secure the resilient arms 12 to the deck 1, but also serve to secure the aprons 9 and 10, riffles 4 and 5, and the sheet 3 in proper relation with respect to said deck.

Mounted on the beams 11 are brackets 15, 95 and suitably journaled therein is a drive shaft 16, upon which are mounted adjustable eccentrics 17, preferably two being employed.

Depending from the ends of the deck 1 are ears 18, and pivotally therewith are the forward ends of the pitmen 19, the rear ends of 100 which being provided with straps 20 for engagement with the eccentrics 17 in the usual manner.

It is essential that the apron 7 be adjust- 105 able horizontally and vertically, and in order to accomplish this the sides 6 are formed with horizontal slots 21 while the apron has its sides provided with vertical slots 22. Thus the apron may be adjusted horizontally 110 or vertically so that the flange 8 may be moved toward or away from the riffles 4 and 5, and vertically with respect to the deck 1.

Carried by one end of the shaft 16 are belt pulleys 23 and 24, the former being fixed 115 thereto while the latter is loose thereon, whereby a belt may be shifted to the loose pulley when it is desired to stop vibrating the deck.

The resilient arms 12 are normally in the 120 positions as shown in full lines in Fig. 3, and upon rotary motion being imparted to the shaft 16 the pitmen 19 will be reciprocated, whereby the deck will be moved forwardly, as will the apron 7, and the arms will flex 125 to the position as shown in dotted lines. It will be obvious that during the vibration of the deck the return movement thereof will be much quicker than the forward movement due to the flexibility of the arms 12 and construction of the eccentric 17, which action 130 being essential in devices of this character.

It will also be observed that the deck will have in addition to the straight vibratory movement, a rocking movement.

Since the eccentrics 17 are adjustable the throw of the pitmen may be readily regulated as desired, thus providing means for regulating the vibratory movement of the deck.

In operation, the shaft 16 is rotated at the desired speed to impart to the deck the proper vibration, whereupon the pulp and wash water is directed from the usual launder upon the apron 7. It will be of course understood that the apron 7 has been adjusted so that the lower edge of the flange 8 will be spaced the proper distance from the deck 1 to suit the class of ore to be separated, whether coarse or fine. For instance, if the ore is fine the flange 8 will be comparatively close to the deck. The apron being rather wide will permit the mineral to settle thereon before leaving the lower edge, after which it will drop onto the deck, while the water will be projected toward the riffle 4.

The water collected on the plane between the flange 8 and riffle 4 will be caused to form waves due to the vibration of the deck 1, whereupon the tailings will pass over the riffle 4 onto the apron 9, where it can be disposed of as desired. The mineral passing under the flange 8 will enter the plane between the flange 8 and riffle 5, the same wave movement being present in this plane. This wave movement will cause the concentrates to pass over the riffle 5, and onto the apron 10 where it may be disposed of suitably.

Any free gold entering the plane between the flange 8 and riffle 5 will collect in the pocket 2, and may be easily removed therefrom when desired.

By placing the flange 8 between the riffles 4 and 5 front and rear planes are provided, and it will be readily seen that the vibration to which the deck is subjected will cause the minerals, which collect on the linoleum sheet 3 to pass from the front plane to the rear plane. While material other than linoleum may be used for covering the deck, it has been found from actual experience that linoleum has sensitive holding action on minerals.

What is claimed is:

1. In a separator of the class described, the combination with a deck having front and rear riffles, an inclined apron having a vertical depending flange positioned between the riffles, means whereby the apron and thus the flange can be adjusted vertically or horizontally toward or away from either riffle and toward or away from the deck,

said flange serving to separate the deck space into front and rear planes, communication between the front and rear planes being had under the flange, and means for vibrating the deck to cause wave movements of the water in the front and rear planes.

2. In a separator of the class described, the combination with a deck having front and rear riffles, of end plates fixed to the deck and abutting the ends of the riffles, an inclined apron adjustably connected with the end plates and having a vertical depending flange adapted to be positioned between the riffles and spaced from the deck, said flange serving to separate the deck space into front and rear planes, communication between the front and rear planes being had under the flange, each riffle having a discharge apron associated therewith, and means for vibrating the deck to cause wave movements of the water in the front and rear planes, as and for the purpose set forth.

3. In a separator of the class described, the combination with a deck having front and rear riffles, of end plates fixed to the deck and abutting the ends of the riffles, an inclined apron having a vertical depending flange positioned between the riffles, means carried by the apron and end plates, whereby the apron and thus the flange can be adjusted vertically or horizontally toward or away from either riffle and toward or away from the deck, said flange serving to separate the deck space into front and rear planes, communication between the front and rear planes being had under the flange, each apron having a discharge apron associated therewith, and means for vibrating the deck to cause wave movements of the water in the front and rear planes, as and for the purpose set forth.

4. In a separator of the class described, the combination with a deck having a fabric covering, front and rear riffles resting on the covering, aprons engaged with the under surface of the deck, resilient arms for supporting the deck and having their upper ends engaged with the aprons, clamping bolts passing through the arms, aprons, covering and riffles to hold the same engaged with the deck, an inclined apron adjustably associated with the deck and riffles, and means for vibrating the deck.

In testimony whereof I have hereunto set my hand in presence of two subscribing witnesses.

GEORGE W. ARNOLD.
